US0D1045234S

(12) **United States Design Patent** (10) Patent No.: **US D1,045,234 S**
(45) Date of Patent: ** Oct. 1, 2024

(54) **ANKLE PROTECTOR**

(71) Applicant: **József Lajos Simon**, Budapest (HU)

(72) Inventor: **József Lajos Simon**, Budapest (HU)

(**) Term: **15 Years**

(21) Appl. No.: **35/515,025**

(22) Filed: **Jun. 27, 2022**

(80) **Hague Agreement Data**

Int. Filing Date: **Jun. 27, 2022**

Int. Reg. No.: **DM/222798**

Int. Reg. Date: **Jun. 27, 2022**

Int. Reg. Pub. Date: **Aug. 26, 2022**
